[57] CLAIM

The ornamental design for a kaleidoscope, as shown and described.

DESCRIPTION

FIG. 1 is a perspective view of a kaleidoscope showing my new design;

FIG. 2 is a side elevational view thereof, the side opposite being substantially a mirror image;

FIG. 3 is a top plan view thereof;

FIG. 4 is a front elevational view thereof;

FIG. 5 is a rear elevational view thereof; and

FIG. 6 is a bottom plan view thereof.

The broken line showing of irregular members in FIG. 1 represents environment only and has been omitted from FIGS. 2, 3, 4 and 5 for ease of illustration.

FIG. 1

FIG. 2

FIG. 3

FIG. 4

FIG. 5

FIG. 6
